(57) **CLAIM**

The ornamental design for an electrical energy distribution device, as shown and described.

DESCRIPTION

FIG. 1 is a right side view of an electrical energy distribution device, showing our new design;

FIG. 2 is a front view thereof;

FIG. 3 is a left side view thereof;

FIG. 4 is a top plan view thereof; and,

FIG. 5 is a perspective view thereof.

In the drawings, the broken lines are for the purpose of illustrating portions of the electrical energy distribution device that form no part of the claimed design.
